United States Patent Office.

WILLIAM J. CLARK, OF PROVIDENCE, RHODE ISLAND.

Design No. 4,025, dated May 17, 1870.

DESIGN FOR A TRADE-MARK.

The Schedule referred to in these Letters Patent and making part of the same

---

I, WILLIAM J. CLARK, of the city and county of Providence and State of Rhode Island, have invented and produced a new and original Design for a Trade-Mark, of which the following is the specification.

My design consists of a card-label circular or wrapper, having at the top a picture of the celebrated horse "Dexter," being driven to sulky, with the word "GO" 2.17 $\frac{1}{4}$ in letter-press above the picture on the right, and, beneath the picture, the words, "Dr. A. J. Hopkins' Improved Magic Healing Powder," in letter-press.

Claim.

I claim as my invention—
The design for a trade-mark, as described and shown.
In testimony whereof I have hereunto subscribed my name this 4th day of December, A. D. 1869.

WILLIAM J. CLARK.
